FRONT PANEL FOR WALL OVEN AND BROILER UNIT

Thomas D. Tweedie, Monrovia, and Gene H. Cripe, Studio City, Calif., assignors to O'Keefe & Merritt Co., Los Angeles, Calif., a corporation of California

Application February 9, 1959, Serial No. 54,531

Term of patent 14 years

(Cl. D81—25)

Fig. 1 is a front elevational view of a front panel for a wall oven and broiler unit showing our new design;

Fig. 2 is a side elevational view of the front of the wall oven and broiler unit;

Fig. 3 is an enlarged, fragmentary front elevational view of one extremity of one of the handle elements;

Fig. 4 is a perspective view of one extremity of one of the handle elements; and

Fig. 5 is a top plan view of one extremity of one of the handle elements.

We claim:

The ornamental design for a front panel for wall oven and broiler unit, as shown.
